United States Patent Office.

WILLIAM HAWKINS, OF BROOKLYN, NEW YORK, ASSIGNOR TO
HIMSELF AND F. W. BARNHART, OF SAME PLACE.

Letters Patent No. 91,128, dated June 8, 1869.

IMPROVED SEPARATOR FOR MEAL, &c.

The Schedule referred to in these Letters Patent and making part of the same.

To all whom it may concern:

Be it known that I, WILLIAM HAWKINS, of Brooklyn, in the county of Kings, and State of New York, have invented and made a new and useful Improvement in Separators for Meal, &c.; and I do hereby declare the following to be a full, clear, and exact description of the said invention, reference being had to the annexed drawing, making part of this specification, wherein—

Figure 1 is a longitudinal section of the said separator, and

Figure 2 is a cross-section of the same.

Similar letters denote the same parts.

Sieves and sifters of different kinds have been made, but usually any foreign matter that may be retained in the sieve has to be emptied by inverting said sieve.

My invention relates to a peculiarity in the sifting-apparatus, whereby the operation is made continuous, the meal, or similar material, being delivered at one place, and the material that does not pass through the sieve at a separate opening.

My invention consists in a shaft, set in adjustable bearings, and carrying elastic agitators and inclined conveyers, combined with a case having a semicircular screen at the bottom, a hopper for receiving the meal or material passing through the sieve, and an opening at the end of the semicircular screen, through which the conveyers deliver the unsifted material.

In the drawing—

a is a shaft, to be revolved by competent power.

The pulleys *b* and *c*, and belt, allow the machine to be driven by hand-power applied to the crank-handle *d*.

The shaft *a* is set in bearings *e f*, within the frame

g, and *h i* are adjusting-screws for these journal-boxes.

Between the frames *g* are the side pieces *k* and top *l*, forming the case, and *m* is the semicircular sieve, placed between the sides *k*, and over the hopper *n*, that receives and delivers the meal or other material sifted through *m*.

Upon the shaft *a* there is a series of elastic agitators, *o o*, arranged in a spiral position between the inclined conveyers *p p*, which also form a spiral or screw form upon the shaft *a*, so that the material will be caused to progress from the end at which it runs in from the hopper *q*, to the end where the unsifted material is delivered from the separator by the spout *r*.

It will be understood that this apparatus is especially intended as a light portable separator, for family use, and the operation being continuous, greatly facilitates its use.

The inclined conveyers also act as agitators, and the elastic agitators *o o* act to force the meal through the sieve, and by their contact with the sieve, to keep the same from becoming clogged.

What I claim, and desire to secure by Letters Patent, is—

The shaft *a*, with the agitators *o*, and inclined conveyers *p*, arranged as set forth, in combination with the adjustable bearings *e f*, case *k l*, screen *m*, hopper *n*, and delivery-spout *r*, as and for the purposes set forth.

In witness whereof, I have hereunto set my signature, this 10th day of May, 1869.
